CLAIM

The ornamental design for decorative clothing appliquéd, as shown and described.

DESCRIPTION

FIG. 1 is a perspective view of the decorative clothing appliquéd of the present invention;

FIG. 2 is a front view of the decorative clothing appliquéd of the present invention;

FIG. 3 is a right side view of the decorative clothing appliquéd of the present invention with the left side being a mirror image thereof;

FIG. 4 is a top view of the decorative clothing appliquéd of the present invention with the bottom being a mirror image thereof;

FIG. 5 is a rear view of the decorative clothing appliquéd of the present invention;

FIG. 6 is a perspective view of the decorative clothing appliquéd shown in a position of use; and,

FIG. 7 is an exploded perspective view showing installation of the decorative clothing appliquéd of the present invention.

The broken lines in the drawings represent unclaimed portions of the decorative clothing appliquéd. The broken line structures shown in FIGS. 6 and 7 are included for the purpose of showing the decorative clothing appliquéd in a position of use and form no part of the claimed design. The broken line arrow in FIG. 7 shows the direction of assembly and forms no part of the claimed design.
